FIG. 1.

FIG. 2.

FIG. 3.

INVENTOR
H. P. Ober,
BY
Neil F. Weston,
ATTORNEY

UNITED STATES PATENT OFFICE

HERMON P. OBER, OF ROCHESTER, NEW YORK, ASSIGNOR TO GENERAL RAILWAY SIGNAL COMPANY, OF ROCHESTER, NEW YORK

CONNECTING MEANS FOR ELECTRIC CONDUCTORS

Application filed October 22, 1927. Serial No. 228,025.

This invention relates in general to terminal connecting means for electric conductors and has more particular reference to a conduit outlet block, and cap therefor, for making connection between parkway cable or other conductor, and wires leading, for example, to track rails, signals, switch boxes, etc., as used in railway practice, or to any other desired means.

10 It is usual practice to run cable underground and bring it up to the surface at the point where power is to be used by passing it up through upright risers. This invention consists essentially in an insulating block 15 which can be readily assembled on, and removed from, such a riser as it exists in the field, together with a protecting and holding cap.

Among the objects sought to be accomplished by this invention are, to produce such a device which is simple, economical to make, easy to install and to take down, and extremely practical in use.

With the ordinary method of connection 25 used in such cases, the apparatus assembled on the top of the riser is either a box or its equivalent, so that the conduit space below such block is made practically inaccessible or at least requires considerable time and effort 30 to be made accessible. With the present invention however, the terminal block can be readily separated from the riser a sufficient distance to permit inspection of the wires in the riser and the filling of the riser with sealing compound, all without disconnecting the wires from the terminal block.

A further object of this invention is to provide means for preventing flooding of upright risers by water and this is accomplished 40 by so forming the cap as to have it extend sufficiently below the upper end of the riser to form an air seal against entrance of water into the riser in the event, for example, of the 45 trackway being flooded.

Further objects, purposes and characteristic features of this invention will appear as the description progresses, reference being had to the accompanying drawings showing, 50 solely by way of illustration, one form which

the invention can assume. In the drawings:

Fig. 1 is a sectional plan view of the device taken on line 1—1 of Fig. 2 and viewed in the direction of the arrows.

Fig. 2 is an elevational view, with parts shown in section and

Fig. 3 is a detail view of the terminal block.

Referring to the drawings, at 1 is shown a vertical riser of any usual or desired form 60 containing a cable 2, shown in the present instance as comprised by two conducting wires 3 and 4.

The riser 1 has a portion cut away at one side of its upper end by means of a vertical 65 cut parallel to the axis of the riser forming a vertical face 5 and a transverse cut forming a face 6, to thereby cut out an integral section of the riser. A transverse notch 7 is formed in the face 5, as shown in Fig. 2, the 70 notch having slightly rounded edges for facilitating assembling of the terminal block, as described below.

Formed to be set into the above described portion of the riser 1 is a block indicated in 75 its entirety by B. This block is formed of composition board or any other suitable insulating material. The block comprises a main face portion 8 of generally rectangular form, having an inwardly extending shelf portion 9 near its lower edge with aperture 10 therein for receiving binding posts 11, and having holes 12 formed in the face portion 8 for accommodating outlet wires 3¹ and 4¹. Formed on the inner surface of the portion 8 is a rib 13 of a configuration to readily and accurately set into the notches 7 formed in the 80 riser 1, while extending below the shelf portion 9 of the block B is a toe 14, as shown in dotted lines in Fig. 2.

The block B is assembled in the cut out portion in the riser 1, to take the position shown in Fig. 2, with the rib 13 received in the notches 7, and the downwardly projecting toe 14 bearing against the inner side of the 95 riser below the transverse face 6 of the cut out portion.

Setting over the upper end of the riser 1 is a cap 15, held in place by a set screw 16, the cap having a portion with a general rec- 100

tangular configuration 17 to match the outer surface of the part 8 of block B, in the manner shown in Fig. 1 whereby the cap closely embraces the block when in its assembled position to aid in holding the block against movement. A bulged out portion 18 is formed on the cap for accommodating the outlet wires, and the lower edge 19 of the cap extends downwardly, a short distance below the face 6 of the cut out portion of the riser, for a purpose explained below.

The wires 3 and 4 of cable 2 are attached to the binding post 11 carried by block B, after having described an upwardly directed, 15 long loop 20, as shown in Fig. 2, while the outlet wires 3¹ and 4¹ are attached to the respective binding posts 11 and pass out through the apertures 12 of the outlet block and through the outwardly bulge portion 18 of 20 cap 15.

The cable 2 can be sealed into the riser in the usual manner by pouring a sealing compound into the riser so as to completely fill it to a desired level, as indicated by dotted line 25 21, to seal the wires of the cable and prevent foreign matter from dropping down into the riser.

With the construction described above it will be obvious that with the riser filled with 30 sealing compound as indicated at 21, and with the cap 15 having its lower edge 19 extending down below the lower edge of the cut out portion of the riser, an effective air seal is provided against entrance of water 35 into the riser in the event of flooding of the trackway.

The block B is held in its assembled position against movement in any direction by the cap 15 embracing the upper end thereof 40 and by the interaction of the ribs 13 with the notches 7 and of the downwardly projecting toe 14 and the interior surface of the riser 1. The block can move neither upwardly or 45 downwardly, sidewise of the riser 1, or outwardly thereof, when cap 15 is in place.

For inspecting the wire connections, however, for filling the riser with sealing compound, or for any other desired purpose, easy access is attainable by merely loosening the 50 set screw 16, removing the cap 15, and lifting outlet block B away from the riser 1. The long wire loop 20 formed by wires 3 and 4 permit removal of the outlet block a considerable distance from the riser without necessitating disconnecting the wires therefrom.

This invention thus provides a simple form of insulating block, readily assembled on and disconnected from, a riser, which can be easily prepared for receiving the block by 55 merely taking out a small section thereof to form a receiving cut out portion, and permits ready inspection of the cables placed inside the riser and of the various wire connections, while at the same time all parts are protected 60 against entry of foreign matter and are

sealed against entry of water upon flooding of the trackway.

The above rather specific description of one form of this invention has been given solely by way of example, and is not intended, in any manner whatsoever, in a limiting sense. Obviously, the invention can assume many different physical forms, and is susceptible of numerous modifications, and it is intended that the present application cover 75 all such forms and modifications as come within the scope of the appended claims.

Having described my invention I now claim:

1. In cable connecting means, a hollow 80 riser, a cut out portion in one side of the riser, an outlet block of insulating material, loosely inserted into said cut out portion, means sealing the riser below the cut-out portion, and a cap fitting over the end of the 85 riser and bearing against the outlet block, the lower edge of the cap extending below the lower edge of the cut out portion whereby to form an air seal against water entering the riser.

2. In cable connecting means, a hollow 90 riser, a cut out portion in one side of the riser, an outlet block of insulating material loosely inserted into said cut out portion, means sealing the riser below the cut-out portion, a cap fitting over the end of the riser and bearing against the outlet block, the lower edge of the cap extending below the lower edge of said cut out portion, and sealing compound closing the riser below said outlet 100 block, whereby to form an air seal against water entering the riser.

3. In cable connecting means, a hollow cylindrical riser, a substantially straight edge cut out portion in one side of the riser, 105 an outlet block of insulating material having all its faces substantially plane and loosely inserted into said cut out portion, conductor connecting means carried by the block, and a cap fitting over the end of the riser and bearing against the outlet block.

4. In connecting means for cable, a hollow 115 riser, a cut out portion at the upper end of the riser, an outlet block loosely fitting into the cut out portion and extending into, and only part way across, the riser, and a cap removably fitting over the end of the 120 riser and around the block.

5. In connecting means for cable, a hollow 125 riser, a cut out portion at the upper end of the riser, an outlet block loosely fitting into the cut out portion and extending into, but only part way across, the riser, whereby to leave room in the riser for cable to run past the block, and a cap removably fitting over 130 the end of the riser and around the block, conductor connecting means carried by the block, and a cable fastened to said connecting means after it has described a long loop, whereby, upon removal of said cap, said out-

let block can be readily separated a considerable distance from the riser without necessitating disconnecting cable therefrom.

6. In connecting means for cable, a hollow riser, a portion cut out of one side of the riser by a cut parallel with the axis of the riser and a cut transverse to such axis, a transverse notch cut out of the edge formed by the said parallel cut, and a cable outlet block fitting 10 into said cut out portion and having portions for fitting into said transverse notch.

7. In connecting means for cable, a hollow riser, a portion cut out of one side of the riser 15 by a cut parallel with the axis of the riser and a cut transverse to such axis, a transverse notch cut out of the edge formed by the said parallel cut, and a cable outlet block fitting into such cut out portion and having an inwardly extending part carrying connecting 20 means for attachment thereto of cable.

8. In connecting means for cable, a hollow riser, a portion cut out of one side of the 25 riser by a cut parallel with the axis of the riser and a cut transverse to such axis, a transverse notch cut out of the edge formed by the said parallel cut, a cable outlet block fitting into such cut out portion, a projecting 30 rib on the block fitting into said transverse notch, a depending toe extending below said transverse cut when the block is in position in the riser, and a cap removably fitting over the end of the riser and the block, and having a configuration to match that of 35 the block, whereby to aid in holding the block in position on the riser.

9. In connection means, a hollow riser, a 40 cut out portion in one side of the riser at its top, an outlet block loosely inserted in the cut out portion, a removable cap fitting over the end of the riser and embracing said block, terminal posts on the block to which cable can be connected, outlet means in the block 45 and the cap for lead out wires, sealing compound filling the riser to a level below the block, the lower edge of the cap extending well below said cut out portion of the riser.

10. In connection means, a hollow riser, a 50 cut out portion in one side of the riser at its top, an outlet block loosely inserted in the cut out portion and extending only part way across the riser, a removable cap fitting over the end of the riser and embracing said block, 55 terminal posts on the block, and outlet means in the block and the cap for lead out wires.

11. An outlet block of insulating material 60 for use with conduit risers, comprising, a generally rectangular face portion, a shelf extending away from, and connected to, the lower part of the face portion, a toe offset from the face portion and extending from, and substantially parallel to, the face portion and to one side of said shelf, and a rib 65 spaced from the shelf and extending from

the face portion substantially parallel to the said shelf.

12. An outlet block of insulating material 70 for use with conduit risers, comprising, a generally rectangular face portion, a shelf extending away from, and connected to, the lower part of, the face portion, a toe offset from the face portion and extending from, and substantially parallel to, the face portion and to one side of said shelf, and a rib spaced 75 from the shelf and extending from the face portion substantially parallel to the said shelf, said toe and said rib being positioned at opposite sides of said shelf.

In testimony whereof I affix my signature. 80
